WALL AND CEILING COVERING.

No. 19,670.

Patented Feb. 25, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,670, dated February 25, 1890.

Application filed December 26, 1889. Serial No. 335,042. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of perpendicular bands 1, having bands 2, from which spring scrolls 3, and also a flower on stalk 4. One termination of the scroll is a

ribbon 5. The figure of the scroll is repeated at regular distances.

15 The groundwork of the design is granular.

What I claim is—

The design for a wall and ceiling covering herein shown and described, consisting of scrolls connected by bands, and general ornamentation with festoons, buttons, branches of leaves, and flowers.

PAUL GROEBER.
